Primary Examiner — Khawaja Anwar*Assistant Examiner* — Julice Seung Eun Oum(74) *Attorney, Agent, or Firm* — LegalForce RAPC Worldwide(57) **CLAIM**

The ornamental design for a tricep strap, as shown and described.

DESCRIPTION

FIG. 1 is a front left side perspective view for a tricep strap, showing our new design;

FIG. 2 is a front right side perspective view of FIG. 1 thereof;

FIG. 3 is a front elevational view of FIG. 1 thereof, the rear elevational view being a mirror image; and,

FIG. 4 is a left side elevational view of FIG. 1 thereof, the right side elevational view being a mirror image.

The broken lines indicate unclaimed portions of the tricep strap and form no part of the claimed design.

1 Claim, 4 Drawing Sheets(56)
